UNITED STATES PATENT OFFICE.

GUSTAVE SCHMIDT, OF CINCINNATI, OHIO.

HAME-TUG.

SPECIFICATION forming part of Letters Patent No. 367,066, dated July 26, 1887.

Application filed February 7, 1887. Serial No. 226,761. (No model.)

To all whom it may concern:

Be it known that I, GUSTAVE SCHMIDT, of the city of Cincinnati, county of Hamilton, and State of Ohio, have invented a new and 5 useful Improvement in Hame-Tugs, of which the following is a full, clear, and exact description, reference being had to the accompanying drawings, forming part of this specification.

My invention relates to an improvement in 10 hame-tugs for fastening a harness-trace to the hames or hame-clip, the novel features of which will be more fully set forth hereinafter.

In the accompanying drawings, Figure 1 is 15 a side elevation, in section, of my improved hame-tug attached to the clip. Fig. 2 is a side view of the coupling-plate and the harness-clip. Fig. 3 is a top plan view of the same. Fig. 4 is a modified form of the end of coupling-plate.

20 Like letters of reference indicate identical parts in the different figures.

A is an ordinary hame-clip attached to the hames by the loop A'. This clip usually consists of two arms of malleable metal, A A, attached to the hames by the loop A'. These arms A A are inserted between the strips of leather of which the tug is made and there riveted, or in heavy harness they sometimes embrace the tug, both arms being on the out- 25 side. When so constructed, it is difficult to attach them to the tug by rivets in a neat or secure manner, and unless the clips extend throughout the entire length of the tug the tug is left weak and liable to crack or break 30 when bent. When the clip is made long enough to extend the entire length of the tug, it is heavy and awkward and prevents making a neat job, and the buckle-loop and buckle cannot be securely and neatly fastened on.

40 In my improved tug I provide a coupling-plate, B B', which consists of a flat strip of malleable metal of about the same length as the tug, or a little less, the rear portion, B', being a little wider than the front portion, B, but narrow enough to be inserted between the 45 seams which fasten together the strips of leather, C C' C'' C'', of which the tug is made. A portion of the plate, as at D, is cut away to make it lighter. The front portion, B, is made 50 narrower and on a slightly-different plane, the

two parts being joined together at F, with, if desired, a slight shoulder, F'. The front end, as at G, is made thick enough to secure the proper space between the arms of the clip A and to form a solid base for the lug E, which are cast integral with the plate B, extending up from it on both sides, so as to catch in holes in the arms of the clip, the lugs E and the plate being a single piece of metal.

The lug E, if preferred, may be riveted—that 50 is, its ends spread by a blow after they are in place—so as to retain the clip more securely, though that is not necessary. The plate B is inserted between the arms A of the clip, which are provided with holes to receive the lugs E.

These lugs hold the clip and the coupling-plate 55 securely together. The shorter arm of the clip A is fitted to the forward end of the plate B, where it is held in place by the clamps K.

The coupling-plate and clip are then inserted in the end of the tug, as shown in Fig. 70 1, one or more layers of the leather, as C C'', fitting in the spaces formed by the shoulders at G and F.

The outer layer of leather, C, is made short to have room for the buckle-loop 75 M, which is passed loosely over the wide portion of the coupling-plate B'. The buckle N is fastened to the rear end of the plate by the leather strap P and rivet p, and holds the buckle-loop M in place without any stitching.

80 Where fine work is required, the end of the plate is made narrow, as shown in Fig. 4, so as to be inserted between the strips of leather, and the metal be thus covered and hidden. The tug is then ready for the attachment of 85 the trace by the buckle N. By this attachment I can fasten the tug to any ordinary form of hame-clip with very little trouble without sewing or riveting. The buckle-loop is held in place by the buckle without stitching or riveting,

90 and by loosening the single rivet p all the parts can be taken apart instantly for repair without any ripping or resewing, &c. It braces and supports the tug and makes a stronger and neater tug, combining strength, 95 elasticity, simplicity, and great economy in manufacture or repairing.

Having thus fully described my invention, what I claim, and desire to secure by Letters Patent, is—

1. In a hame-tug, the coupling-plate B B', adapted to fit between the arms of the hame-clip, having the lugs E E and clamps K K for attaching the clip, substantially as and for the purpose described.
2. In a hame-tug, the coupling-plate B B', provided with shoulders F' and spacing-shoul-
- der G, carrying the lugs E E, substantially as and for the purpose described.

GUSTAVE SCHMIDT.
